UNITED STATES PATENT OFFICE.

WILLIAM ROBERT DRAYTON INNES, OF MELBOURNE, VICTORIA, AUSTRALIA, AND MALCOLM SHORE STANLEY, OF ADELAIDE, SOUTH AUSTRALIA, AUSTRALIA, ASSIGNEES TO JAMES BELL & CO. PROPRIETARY LIMITED, OF MELBOURNE, VICTORIA, AUSTRALIA, A COMPANY REGISTERED UNDER THE LAWS OF VICTORIA.

CONSTRUCTION OF REINFORCED CONCRETE FLOORS.

Application filed October 26, 1923, Serial No. 670,975, and in Australia April 24, 1923.

This invention relates to the construction of monolithic reenforced concrete floors, and in particular it comprises a construction embodying the use of light tiles as applied to floors constructed on the flat slab principle, whereby the use of main and secondary girders is eliminated but the use of dropped panels over the tops of the columns is retained where necessary. The hollow tiles are permanently retained as part of the floor.

A finished floor constructed according to this invention comprises a number of narrow ribs of concrete extending across the spaces between solid concrete slabs positioned over the tops of the supporting columns, such ribs crossing one another approximately at right angles and having flared or gradually thickened ends merging into such solid slabs, with a lightly reenforced layer of concrete covering and connecting the tops of the ribs and slabs and forming the floor surface, the ribs and the slabs having embedded within them suitable reenforcements, and the spaces between the sides of the ribs being filled by light tiles.

In order that our invention may be clearly understood we will describe the same with reference to the accompanying drawings in which

Fig. 1 is a plan view partly in section of portion of a floor constructed according to our invention, and

Fig. 2 is a cross section on line 2—2 of Fig. 1.

In constructing a floor according to this invention a temporary centering is erected to carry the floor while it is being laid. This centering may be constructed after any usual or approved manner and is not shown in the drawings. Upon this temporary centering are placed a number of hollow tiles A arranged in rows around the tops of the supporting columns B with spaces between them forming troughs for the ribs C in which suitable reenforcements D preferably of steel rod are laid.

The tiles A are placed only over the spaces between the tops of the columns, leaving a clear space immediately over and adjacent to the top of each column. Tiles of various shapes may be used but rectangular ones are simple and economical to produce.

Around the edge of each of the beforementioned spaces is placed a row or border of tiles A¹ of diminishing width with spaces between them for the reenforcements. Preferably prismatic or tapering hollow tiles are used placed with their narrow faces towards the column as shown in Fig. 1. More than one row of such tapering tiles may be used, or several rows of tiles progressively reduced in size to form a gradually increasing space for the concrete. Within such row or border of diminishing tiles there remains over the top of each column a plain space which is subsequently filled with concrete forming a solid slab C³ immediately over and extending in cantilever form from the top of the column.

Suitable reenforcements are laid in the troughs or spaces between the tiles and across the tops of the columns, and very light reenforcements are laid across the tops of the tiles. Concrete is then filled into such spaces and a covering layer spread over the ribs, the tiles and the cantilever slab.

In the case of a heavily loaded floor it may be considered advisable to use a dropped panel over the top of the column by increasing the thickness of the cantilever slab as shown in Fig. 2.

The effect of this mode of construction is that when the concrete is placed between and over the tiles and reenforcements and over the columns and fills the spaces it produces a number of comparatively narrow concrete ribs C between the tiles with flared or gradually thickened ends C¹ merging into solid concrete slabs C³ over the tops of the columns and with a covering layer of concrete over and connecting the tops of the ribs and slabs and forming the floor surface. The tiles form a permanent part of the floor and, after the centering has been removed, the undersides of the ribs and of the tiles being level one with the other will show a plain soffit for the ceiling of the room beneath.

These thickened ends C¹ of the concrete ribs between the tiles give additional resistance against shearing stresses at the edges of the column slabs. The greater depth of floor slab permitted by the use of hollow tiles imparts to the floor additional stiffness against deflection. It reduces the deadweight of the floor to a minimum. It

permits of the application of flat slab floors to structures with greater economy than is possible by the use of the solid flat slab.

The expression "tiles" used in this specification is intended to cover blocks of material either hollow or solid and made of various materials such as earthenware, breeze, or other relatively light suitable material.

What we claim is—

- 10 A monolithic reenforced concrete floor composed of a number of solid concrete slab portions positioned over the tops of the columns which support the floor, a number of concrete ribs extending across the spaces between such slab portions and crossing one another approximately at right angles,

whereby to surround the slabs, the ends of said surrounding ribs gradually thickened toward the slabs or ribs and merging into said slabs, light tiles positioned between such ribs, suitable reinforcements embedded in the slab portions and ribs, and a lightly reinforced layer of concrete covering and connecting the tops of the ribs and slabs and forming the floor surface, the whole forming 20 an integral floor structure.

In testimony that we claim the foregoing as our invention we have signed our names this 4th day of September, 1923.

WILLIAM ROBERT DRAYTON INNES.
